UNITED STATES PATENT OFFICE.

ROBERT M. FOTHERINGHAM, OF BUFFALO, NEW YORK.

FEED-MACHINE FOR SURFACE-DRESSING.

1,249,608.

Specification of Letters Patent. Patented Dec. 11, 1917.

Application filed January 26, 1917. Serial No. 144,665.

To all whom it may concern:

Be it known that I, ROBERT M. FOTHERINGHAM, a citizen of the United States, residing at Buffalo, in the county of Erie and State of New York, have invented certain new and useful Improvements in Feed-Machines for Surface-Dressing; and I do hereby declare the following to be a full, clear, and exact description of the same, such as will enable others skilled in the art to which it appertains to make and use the same, reference being had to the accompanying drawings, and to figures of reference marked thereon, which form part of this specification.

Like figures of reference refer to like parts.

My invention relates to feed machines for surface dressing, wherein the surface to be dressed is fed to a buffing, a polishing, or a grinding wheel, which revolves about a fixed axis.

One object of my invention is to provide for automatically feeding articles of a variety of shapes and sizes to the dressing wheel, while controlling the pressure therebetween, these means being adapted to present any part of the work to the dressing wheel.

30 A further object of my invention is to provide means to rotate the work upon a movable axis, so as to present varying contours of the piece of work, rotatively, to the dressing wheel.

35 A further object is to provide means for governing the position of the movable axis upon which the work is rotated, so as to maintain a good contact of the work with the dressing wheel during the application of 40 any part of the whole surface to be worked upon.

A further object of my invention is to provide, with means for rotating the work and means for governing its contact with the 45 dressing wheel, other means capable of giving the work a reciprocating longitudinal movement along its axis of rotation, so that all of the surface of a piece to be operated upon, may be applied to an operating wheel, 50 narrower than the said piece.

A further object is to provide means for 55 releasably fixing, in a ready manner, the work in the feed machine, for surface dressing, whereby a plurality of like pieces can be successively placed and replaced in the feed machine, without disturbing the syn-

chronism of the adjusted operating parts, after the feed machine has once been set for handling a given shape and size of piece to be operated upon, by the dressing wheel. 60

A further object of my invention is to adapt the mandrel to changes of angular position, relative to the face of the feed machine, whereby surfaces, at an angle to the axis of rotation of the piece of work, may be 65 readily applied to the dressing wheel.

A further object of my invention is to provide motor driven means for carrying out any and all of the foregoing objects.

With these and other means in view, my 70 invention includes certain details of construction, affording means for automatically positioning the work to the dressing wheel.

These means include a controlling cam, having its operating surface of a shape conforming to that of the object worked upon. 75 This cam is connected with the mandrel, which holds the work by means of intervening mechanism. The movement of the cam is synchronized with that of the work and is 80 governed by means of a spring pressed roller, in contact with the cam. The pressure of contact of the work with the operating wheel is thus maintained, while the work is automatically presented to be operated upon. 85

Means are provided for longitudinally reciprocating the work, when a dressing wheel, narrower than the piece operated upon, is used. In addition to the above, means for 90 enabling the operator to readily apply and release the work from the feeding machine, are also provided.

The form of my invention illustrated in the drawings is hereinafter described, and 95 what I claim is set forth.

Figure 1. is a front elevation of a feed machine embodying my invention.

Fig. 2. is a sectional plan of the spring holding device adapted to releasably hold 100 the work on the chuck.

Fig. 3. is a detached elevation showing a simple mandrel connection for the work, eliminating the variable angle attachment.

Fig. 4. is a side elevation of the machine, 105 partly in section.

Fig. 5. is a part sectional elevation of the oscillating member, and the attached bracket, showing the racks and gears for effecting the reciprocating movement. 110

Fig. 6. is a top plan of the machine.

Fig. 7. is a fragmentary view of the ma-

chine showing the motor, gearing connections and journaling of the oscillating frame.

Shown in the figures, is a bed plate 5 marked 1, having supporting rollers or casters 2, 2, and screw jacks 3, 3, adapted to support the machine above the floor off the rollers or casters 2, 2, after the machine has been properly positioned to coöperate with 10 the dressing wheel 4. Each jack screw 3 has a hand wheel 5, for releasably applying the jacks. Mounted upon the bed plate 1, is the electric motor 6, having a shaft 7, and a small gear 8, fixed thereto. An oscillating 15 member 9, having a base 10, is supported by its trunnions 11, and 12, journaled in bearings 13, and 14, respectively; these bearings being co-axial with the motor shaft 7. Between the oscillating member 9, and its base 20 10, is a bearing plate 15. Clamp screws 16, 16, rigidly clamp the three parts—9, 10 and 15, together at the flange 17.

A reduction in speed from the motor 6, to the transmission gearing of the feed machine, is obtained through the meshing of 25 the pinion 8, with the large gear 18, and the pinion 19, with the large gear 20; the pinion 19, being fixed to or integral with the gear 18, which together are journaled on the 30 shaft 21, fixed, in the member 9, free from and above the upper part 22, of the bearing 13.

The gear 20 is fixed upon the shaft 23, which is journaled co-axially in the trunnions 11, and 12. The shafts 7, and 23, have 35 a common axis also. The shaft 23, passes through the cavity of the base 10, and has fixed upon it, within said cavity, the bevel gear 24, which meshes with the bevel gear 25, on the vertical shaft 26, passing up 40 through and journaled within the bearing plate 15.

From the shaft 23, the transmission gearing is divided into two parts, one part effecting the motion of the work across the 45 face of the dressing wheel, and the other part effecting the rotary motion of the said work. The latter part of the gearing has a branch connection with the governing cam, as will be hereinafter explained.

50 Considering the transmission gearing which effects the longitudinal movement of the work in the line of its axis rotation, beginning with the base 10, an extension 27, has journaled within it a shaft 28, having 55 fixed thereon, at its inner end, a bevel gear 29, meshing with the bevel gear 25, and fixed at its outer end is a pinion 30. In the arm 31, which projects from the column 9, is fixed a shaft 32, having journaled thereon 60 the large gear 33. The face of the large gear 33, has guides 34, 34, forming a radial channel 35, in which is adjustably fixed the crank pin 36, which may be placed at the center of the wheel if the action of the crank 65 pin is nullified.

Fixed near the upper end of the column 9, is the vertical rack bracket 37, having journaled transversely within it a shaft 38, at the outer end of which is socketed the hub 39, engaged by the hand lever 40. On the same shaft is fixed the pinion 41, by the locking pin 39^a, and meshing with the sliding rack bar 42, in the vertical rack bracket 37. Fixed upon the rack bar 42, is the wrist pin 43, connected by the rod 44, with the crank pin 36; the connecting rod 44, being journaled on both pins 36, and 43. At the inner end of the shaft 38, is fixed the bevel gear 45, meshing with a bevel gear 46, fixed upon a sleeve 47, mounted concentrically for rotation upon the shaft 26. At the upper end of the sleeve 47, is fixed a spur gear 48, which meshes with a horizontal rack bar 49, in sliding engagement with the horizontal rack bracket 50, fixed or integral with the swiveling case 51, which is journaled in the upper end of the column 9. Surmounting the casing 51, are two arms 52 and 53, supporting the respective bearings 54, and 55, and having extensions 56, and 57.

Considering next the gearing effecting the rotary motion of the chuck, holding the work, we have the clutch bevel gears 58, and 59, journaled in the bearings 54, and 55, held in longitudinal position by the respective collars 60, and 61, and meshing with the bevel gear 62, on the shaft 26, the slotted shaft 63, journaled for sliding engagement with the clutch bevel gears 58, and 59, and also journaled in the arms 64, and 65, which are fixed at the respective ends of the horizontal rack bar 49. Journaled in the extensions 56 and 57, is the threaded shaft 66, having a hand wheel 67, and a collar 68. The shaft 66, is threaded for part of its length in the center, to mesh with a traveling nut 69, having forked arms 70, 70, journaled in the ends of the arms 70, 70, are collar segment 71, 71, engaging a circumferential groove 72, in the slidable clutch member 73, which is slidably keyed at 74, to the groove 75, in the shaft 63.

Considering the variable angle transmission gearing, connected with the end of the shaft 63, an extension bracket 76, upon the arm 65, terminates in a hinging member 77, to which is pivoted a yoked bracket 78, having a bevel gear idler 79, journaled on the lower pivot pin 80. Fixed on the end of the shaft 63, is the bevel gear 81, meshing with 11 and preferably smaller than the idler gear 79. Journaled in the yoked piece 78, is the short shaft 82, having the bevel gear 83, fixed thereto and meshing with the idler gear 79. At the other end of the shaft 82, is detachably fixed the chuck 84, by means of the set screw 85. 86 is a pan mounted upon the chuck 84, and held thereon by the arm 87.

The following parts comprise those form- 13

ing the spring holding device for holding the work upon the chuck; an extension 88, on the yoke bracket 78, terminates in a T piece 89, having in sliding engagement therewith a tube 90, adjustably fixed thereto by the set screw 91. Near one end of the tube 91, is adjustably fixed the collar 92, by means of the set screw 93. The collar 92, has slots 94, for engagement with the teeth 95, of the adjustable member 96, which member 96 slidably fits the tube 90. Within the tube 90, is the rod 97, slidably keyed on the tube by the key 98, and slidably controlled by the spring 99, fastened to the tube at the 15 point 100.

The outer end of the rod 97 terminates in a threaded stem 101, engaged by a nut 102. The tube 90 extends through the sliding member 96, and is slidably engaged by the 20 nut 102. Extending integrally out from the sliding member 96, is the arm 87, having a centering piece 103, journaled transversely in the end thereof.

In Fig. 3. the extension 88 is inserted in 25 the socket end of the arm 65, and secured thereto by the set screw 105, instead of being attached to the yoke bracket 78, as shown in Fig. 1; thus eliminating the variable angle transmission gearing connected with the 30 brackets 76 and 78. The tube 90, is also provided with internal parts similar to those shown in Fig. 2. The stub end 63^a, of the shaft 63, forms a mandrel in this case for the chuck 84, which is secured to it by the 35 screw 85.

For turning the swiveling casing 51, and all parts above and attached to it, so as to position the pan 86 in or out of contact with the dressing wheel 4, there is provided a 40 worm wheel 106, keyed at 51^a to the upper part of the casing 51, and meshing with a worm 107, fixed on a shaft 108, journaled in a bracket 109, on the column 9. The shaft 108, terminates in a hand wheel 110.

For governing the pressure of contact of the work on the chuck 84, with the dressing wheel 4, there is shown the following mechanism in conjunction with that above described: Journaled in the arm 111, of the 50 bracket 109, on the column 9, is a shaft 112, having fixed at its inner end a bevel gear 113, meshing with a bevel gear 114, keyed to the shaft 26. At the outer end of the shaft 112, is fixed the cam 115, by means 55 of the set screw 116. The bevel gears 113 and 114, are equal in size or miter gears. The bevel gears 58, 59 and 62, are also miter gears, and the gears 81 and 83, are equal in size but not miter gears; therefore the pan 60 86 will make the same number of turns as the cam 115, and the direction of rotation can be determined by meshing the clutch member 73, with either the miter gear 58 or 59.

65 Mechanism governing the position of the

cam 115, is mounted on a standard 117, bolted to the bed-plate 1. Journaled transversely in the upper end of the standard 117, is the threaded shaft 118, secured longitudinally by the hub 119, of the hand wheel 120, and the collar 121, fixed to the shaft 118. In guides 122, 122, in the upper end of the standard 117, is the tubular member 123, having fixed to the under side thereof the threaded nut 124, engaging the threaded 75 shaft 118, for reciprocation of the tubular member 123, as the shaft is turned by the hand wheel 120. Slidably engaged with the tubular member 123, is the threaded spindle 125, having fixed thereon the lock nuts 80 126, 126, abutting against the end of the tubular member 123, and having at its other end the head piece 127, provided with a longitudinal slot 128, adapted to slidably engage an interned key fixed upon the member 123. In the outer end of the head piece 127, is secured the stud 129, on which is journaled the roller 130, engaging the annular recess 131, of the cam 115. There is thus provided a concave operative cam surface 115^a, and a convex operative cam surface 115^b, engaging said roller 130. Compressed within the tubular member 123, and surrounding the spindle 125, is the spring 132.

For balancing the rocking member 9, and its attached parts, I provide a leaf spring 133, fixed at the point 134, to the bed plate 1. The swinging end of the leaf springs 133, is connected by the pair of links 135, 100 to the oscillating member 9.

In operation. Referring to begin with, to Fig. 1. The object to be dressed, such as the pan 86, is mounted upon a suitable chuck 84, upon a mandrel 82. This pan 86, may be 105 secured endwise upon the chuck 84, according to conditions of operation, in the following manner; there is shown in the figures, an extension 88, supporting a tube 90, upon which is slidably engaged a member 96, the 110 member 96, having an arm 87. A tension spring 99, elastically draws the member 96, against a fixed collar 92, and teeth 95, engaging notches 94, in said collar 92, determine the angular position of the arm 87, 115 which in the drawings is shown to be parallel with an extension 88. The centering piece 103, journaled in the end of the arm 87, is thus forced against the pan 86. When it is desired to remove the centering piece 120 103, from contact with the pan 86, the arm 87, is drawn sufficiently out of the tube 90, to release the teeth 95. The arm 87, is next rotated 180 degrees, so that the teeth 95, can change places in engaging the notches 94, 125 and be so held in an upright position as to be free from the article to be dressed, thereby permitting the removal of said article, and the placing of another upon said chuck 84.

The machine as a whole is then rolled on 130

the floor to the vicinity of the dressing wheel 4, and adjusted in position to have the pan 86, properly contact the wheel 4, which is here assumed to be adapted to revolve about 5 a fixed axis.

Having once so positioned the machine, the chuck screws 3, are next forced to the floor by turning the respective hand wheels 5, until the machine is lifted off the rollers 10 or casters 2, thus fixing the position of the machine on the floor with respect to the wheel 4. Prior to setting the machine in this position, the cam 115, is synchronously connected with the chuck 84, by transmission 15 means hereinafter described, which transmission means rotates the cam 115, and the chuck 84, at the same number of revolutions.

The motion of reciprocation along the axis of the chuck 84, is provided for in the following way: Starting with the motor 6, revolving the shaft 7, the speed thereof is reduced through the connected gearing 8, 18, 19 and 20, the gear 20, turning the shaft 23, at a much reduced speed compared with that 25 of the shaft 7. The rotation of the shaft 23, is connected with the vertical shaft 26, by means of the bevel gears 24, 25. Meshing with the bevel gear 25, is the bevel gear 29, fixed on the shaft 28, to the outer end of 30 which is fixed the pinion 30, which in turn revolves the gear 33, journaled on the shaft 32.

For a given limit of motion to the motion of reciprocation to the chuck 84, I position 35 the crank pin 36 properly within the channel 35, thereby governing the throw of the rack bar 42, reciprocating through the agency of the connecting rod 44. This motion of reciprocation of the rack bar 42, is communicated to the shaft 38, by means of the meshing of the pinion 41, with the rack bar 42. This reciprocating motion, somewhat modified according to the design of the intervening mechanism, is transmitted through the 40 gears 45, 46 and 48, to the horizontal rack bar 49, giving a reciprocating motion to all parts connected therewith, including the chuck 84, and the pan 86 thereon. This reciprocating motion enables us to present all 45 parts of the surface of the piece to be operated upon, to the dressing wheel, which in this case may be narrower than the said piece; or a slight reciprocating motion attained according to the design of the intervening mechanism, can then be imparted to the piece of work regardless of the width of the wheel, to prevent scoring in definite planes.

If desired, the pinion 41, may be disconnected from rotation with the shaft 38, by withdrawing the locking pin 39^a, from engagement therewith, whereby the operator will be at liberty to manually reciprocate the piece of work, by oscillating the hand lever 65 40, which engages the socketed hub 39, thus

substituting a manual oscillation of the shaft 38, for the automatic oscillation above described.

Now considering the rotation of the article to be dressed. Starting with the shaft 26, 70 the slidable shaft 63, is rotated by means of the reversible clutch member 73, which is slidably keyed to the shaft 63. Rotation in either one or the other direction may be had, according to the engagement of the member 73, with one or the other of the bevel gears 58, and 59, both of which, meshing with the gear 62, fixed upon the shaft 26, revolve in opposite directions. The member 73, is positioned by turning the hand wheel 67, in 75 either direction as desired, to cause the traveling nut 69, to move in one or the other direction; and causing the member 73, to engage one or the other of the clutch bevel gears 58 or 59. If it is desired to rotate the 80 chuck 84, in direct connection with the shaft 63, then the assemblage of parts shown in Fig. 3. is used, wherein the extension 88, is connected with the arm 65. Where it is desired to rotate the chuck 84, at an angle to 85 the shaft 63, as well as having a common axis therewith, the mechanism shown in Fig. 1. is used, wherein the mandrel 82, is turned by means of the gearing connection engaging the gears 81, 79 and 83, the gear 79 being 90 an idler.

The angular position of the chuck 84, is fixed by fixing the angular position of the yoked bracket 78, with respect to the extension bracket 76. Referring to Fig. 6. In 100 this the pan 86, is shown to have assumed a dotted position 86^a, wherein its mandrel revolves about an axis at right angles to the axis of the shaft 63, thus adapting the pan in position to present a flat face against the 105 dressing wheel 4^a. In order to attain this right angle position of the mandrel with respect to the shaft 63, it is necessary to have the gears 81 and 83, smaller in diameter than the idler gear 79, with which they mesh. 110 If instead of the pan 86, shown in the figures, having rectangular section, an object having conical section is centrally mounted upon the mandrel 82, an element of the conical surface of the object, lying within a horizontal plane coincident with the axis of rotation of the cone, can be made while passing through this plane to be parallel with the axis of the shaft 63; and if this element, while in the said horizontal plane, represents the line of contact of the conical object, with the dressing wheel, then the object can be moved longitudinally by the sliding movement of the shaft 63, in its bearing, and all parts of the conical surface of the 115 object can be presented to a wheel narrower than the length of the conical object.

In regard to releasing the object from the machine or applying one thereto. By turning the hand wheel 110, the worm 107, is ro- 120

tated, causing the worm wheel 106, to rotate, and with it the swiveling casing 51, and all parts attached thereto, thus swinging the pan 86, in or out of contact with the wheel 4, as desired.

5 It will be noticed in connection with Fig. 5, that I have shown ample clearance between the swiveling case 51, and the bearing of the shaft 38, to allow for the necessary 10 angular movements of the parts. Similar spacing for a similar purpose is shown in Fig. 1, in connection with the shaft 112.

Considering next the parts provided to cause the cam 115, to properly function in governing the pressure contact of the pan 86, with the wheel 4. Referring particularly to Fig. 4. The cam 115, is shown having a concave operating surface 115^a, and a convex operating surface 115^b, between which is positioned the roller 130, designed to so 20 fill the space between the two surfaces 115^a and 115^b, as to roll on one thereof when loosely contacting the other. The position of the roller 130, governs the position of the cam 115, and consequently the position of the pan 86. This position of the roller 130, with respect to the standard 117, is fixed by the hand wheel 120, and the nut 124, in engagement with the threaded shaft 118. Positioning the tubular casing 123, with respect to the standard 117, the spring 132, is brought into action by means of the head piece 127, which may be drawn to compress said spring to any amount desired, by means 30 of the nuts 126, which engage the threaded spindle 125, and freely shoulder against the end of the member 123.

Having once adjusted the amount of compression in the spring 132, the member 123 is adjustably positioned to fix the roller 130 in a position to govern the movement of the cam 115, so that if the pressure between the wheel 4, and the pan 86, is so great as to cause the oscillating member 9, to rock back,—causing the surface 115^b to press against the roller 130, the head piece 127, will yield, if the pressure is greater than that to which the spring 132, has been drawn up to by means of the nuts 126, thus practically maintaining the pressure between the wheel 4, and the article 86, with the exception of the small additional amount which is brought about due to the additional compression of the spring 134.

55 If it is desired to put extra pressure upon the wheel 4, or reduce the same temporarily, the operation can be governed by manipulating the hand wheel 120.

In the development of the cam 115, to 60 make it complementary to the surface of the object 86, as said object is positioned upon the mandrel 82, we must take into account the fact that the roller 130, contacts said cam on the opposite side to the point of contact between the object 86, and the wheel 4.

We must also take into account the fact that the mandrel 82, oscillates through a larger arc than the shaft 112, permitting us to make a cam much smaller than if the cam shaft were coincident with the mandrel upon 70 which the object is turned. The contour of the cam may be determined by putting an object to be dressed upon the mandrel 82, and supporting a board or the like, upon the shaft 112, and having a fixed marker contacting said board; then slightly turning the object 86, in contact with the wheel 4, or a fixed surface representing the same, and describing a line upon the said board, which line represents the periphery of the cam 80 which would in operation follow in contact with the axis of the roller 130. Modifications from this peripheral line of the cam, can be made to suit the diameter of the roller used, in arriving at the true contour 85 of the surfaces 115^a and 115^b, so that in operation these surfaces intermittently contacting the roller 130, furnish guides for determining the contact of the object 86, with the wheel 4. 90

The oscillating member 9, is balanced by the leaf spring 133, the action of which spring can be designed to always maintain a contact between the surface 115^b, of the cam 115, thus enabling us to dispense with 95 the internal surface 115^a, and simplifying the construction over that herein shown.

Other modifications of this invention can be made, without departing from the spirit and scope thereof. I therefore do not wish 100 to be confined to the detailed construction herein shown. Hence I claim:

1. In a feeding machine for applying a piece of work to a dressing wheel, a frame, a rocking member, trunnions on said member, journaled with said frame and supporting said member for oscillation thereon, a driven shaft journaled with said trunnions and positioned to have its axis common with the axis of oscillation of said rocking member, a mandrel journaled on said member, adapted to hold a piece of work in position to contact said dressing wheel, intervening mechanism between said driven shaft and said mandrel, whereby said mandrel is given a rotary motion by said driven shaft, other mechanism between said shaft and said mandrel, whereby said mandrel is given a longitudinal reciprocating motion in the direction of its axis by said driven shaft, and means 110 for driving said driven shaft. 115

2. In a feeding machine for applying a piece of work to a dressing wheel, a frame, a rocking member pivoted on said frame, a driven shaft journaled with said rocking member and positioned to have its axis common with the axis of oscillation of said rocking member, a driving shaft having its axis common with an extension of the axis 125 of said driven shaft, transmission mecha- 130

nism connecting said shafts, a mandrel journaled on said member adapted to hold a piece of work in position to contact said dressing wheel, intervening mechanism between said driven shaft and said mandrel, whereby said mandrel is given a rotary motion by said driven shaft, other mechanism between said shaft and said mandrel, whereby said mandrel is given a longitudinal reciprocating motion in a direction of its axis by said driven shaft, and means for driving said driving shaft.

3. In a feeding machine for applying a piece of work to a dressing wheel, a frame, a rocking member, trunnions on said member, journaled with said frame and supporting said member for oscillation thereon, a mandrel journaled on said rocking member, adapted to hold a piece of work in contact with said dressing wheel, means for driving said mandrel, manually adjustable traveling means on said frame and coöperating means connected with said traveling means, adapted to govern, automatically, the pressure between said work and said wheel; said coöperating means being positioned by said traveling through manual adjustment thereof, the movements of said coöperating means being synchronized with the movements of said mandrel by intervening mechanism connecting said means with said mandrel.

4. In a feeding machine for applying a piece of work to a dressing wheel, a frame, a rocking member, trunnions on said member journaled with said frame and supporting said member for oscillation thereon, a mandrel journaled on said rocking member, adapted to hold a piece of work in contact with said dressing wheel, means for driving said mandrel and means adapted to govern automatically the pressure between said work and said wheel, intervening mechanism connecting said last named means with said mandrel, the movements of said last named means being synchronized with the movements of said mandrel by said intervening mechanism.

5. In a feeding machine for applying a piece of work to a dressing wheel, a frame, a movable member engaging said frame, a mandrel journaled on said member, adapted to hold a piece of work in contact with said dressing wheel, means for driving said mandrel, a guiding element, a cam positioned between said dressing wheel and said element and adapted to govern the position of said movable member with respect to said dressing wheel, intervening mechanism between said cam and said mandrel, adapted to synchronize their movement, means acting through said movable member and said cam, to govern the pressure of said piece of work on said dressing wheel, the pressure of said cam against said guiding element being in an opposite direction to the pressure of said

piece of work against said wheel, the cam being so proportioned to the shape of said piece of work, that in its synchronous movement with respect to that of said piece of work on said mandrel, the distance between the center of the cam and its contact point with said guiding element, changes with respect to the distance between the center of the piece of work and the said wheel, in a manner to have one distance increase, while the other distance decreases.

6. In a feeding machine for applying a piece of work to a dressing wheel, having a fixed axis, a frame positively positioned with respect to said dressing wheel, a guiding device positively positioned with respect to said frame, a movable member adjustably positioned with respect to said frame, a holding piece for said piece of work on said movable member, a governing element having a contoured surface in bearing engagement with said guiding device and having a positive connection with said member, intervening mechanism between said governing element and said holding means adapted to synchronize their movements, the contoured surface of said guiding element being conformed to the shape of the piece of work supported in said holding piece, said governing element being so positioned in said machine and so proportioned to said piece of work, as to maintain the desired contact between said piece of work and said wheel, by having its to and fro movements, relatively to said guiding device, during the operation of the machine, occur contrary to the to and fro movements of the piece of work, relatively to the dressing wheel.

7. In a feeding machine for applying a piece of work to a dressing wheel, a frame, a movable member engaging said frame, a sliding shaft journaled on the said movable member, a bevel wheel fixed to one end of said sliding shaft, an extension bracket projecting from said moving member, and positioned near said bevel wheel, a short shaft positioned in said extension bracket at an angle to the said sliding shaft, a larger bevel wheel than the first mentioned one, said larger wheel being on said short shaft and engaging said first mentioned bevel wheel, a yoke bracket pivoted on said short shaft, means for adjustably securing said yoke bracket at an angle with said extension bracket, a mandrel journaled in said yoke bracket at an angle with said short shaft, another bevel wheel, smaller than the said larger bevel wheel, engaging the same, and fitted on said mandrel.

8. In a feeding machine for applying a piece of work to a dressing wheel, a frame, extension means on said frame, a tube adjustably fixed on said extension means, a collar fixed to said tube, an arm slidably mounted upon said tube positioned to con-

tact said collar, an elastic means within said tube adapted to draw said arm against said collar, said elastic means being connected by other means to said arm.

5 9. In a feeding machine for applying a piece of work to a dressing wheel, a frame, said frame having a base and jacks operative on said base, adapted to adjustably support said base off the floor and to fix the 10 position of said machine with respect to the axis of said dressing wheel.

10 10. In a feeding machine for applying a piece of work to a dressing wheel, a frame, said frame having a base, rollers on said 15 base adapted to support the same off a continuously flat floor and to portably carry said machine in any angular direction on said floor with respect to said wheel.

11. In a feeding machine for applying a piece of work to a dressing wheel, a frame, a base to said frame, rollers positioned on 20 said base adapted to support the same off the floor, jack screws, means on said base to raise the same above the floor, and support 25 said base thereon, and to relieve said rollers from said support.

12. In a feeding machine for applying a piece of work to a dressing wheel, a frame, a mandrel shaft on said frame, a reversible 30 clutch connected with said mandrel shaft, adapted to revolve same in either direction.

13. In a feeding machine for applying a piece of work to a dressing wheel, a frame, holding means for supporting said piece of 35 work, means on said frame for journaling a shaft,—a bevel gear on said shaft, a bracket fixed to said means, a pivot pin on said bracket, positioned to have its axis pass transversely through the axis of said shaft, a 40 bracket-piece pivoted upon said pivot pin, a mandrel shaft journaled in said bracket piece, a bevel gear journaled on said pivot pin and meshing with the first mentioned bevel gear, and a third bevel gear meshing with the 45 second mentioned bevel gear and mounted upon said mandrel shaft, said pivot bracket being adapted to be adjustably positioned at various angles with respect to the axis of said first mentioned shaft.

50 14. In a feeding machine for applying a piece of work to a dressing wheel, a frame, means on said frame for journaling a shaft, a bevel gear on said shaft, a bracket fixed to said means, a pivot pin on said bracket positioned to have its axis pass transversely through the axis of said shaft, a bracket piece pivoted upon said pivot pin, a mandrel shaft journaled in said bracket piece, a bevel gear journaled on said pivot pin, larger 55 than and meshing with the first mentioned bevel gear, and a third bevel gear equal in size to the first mentioned bevel gear, meshing with the second mentioned bevel gear, and mounted upon said mandrel shaft, said 60 pivot bracket being adapted to be adjustably 35

positioned at various angles with respect to the axis of said first mentioned shaft.

15. In a feeding machine for applying a piece of work to a dressing wheel, a frame, a crank wheel journaled with said frame, 70 said crank wheel having a crank pin radially adjustably positioned thereon, a rack bracket on said frame, a rack in sliding engagement with said rack bracket, means connecting said rack with said crank pin, 75 a second rack bracket on said frame and a second rack slidably engaging said rack bracket, gearing operatively connecting said racks, whereby the motion of reciprocation is given to said piece of work. 80

16. In a feeding machine for applying a piece of work to a dressing wheel, a frame, a mandrel journaled on said frame, for rotation thereof, rack means on said frame connected with said mandrel, adapted to 85 give the same the motion of reciprocation, a shaft journaled in said frame, a hub on said shaft, a hand lever releasably fixed in said hub adapted for manual oscillation therewith, intervening mechanism between 90 said shaft and said rack means for connecting the oscillations of said shaft to said rack means.

17. In a feeding machine for applying a piece of work to a dressing wheel, a frame, 95 a rocking member pivoted with said frame, the weight of said rocking member being above its pivotal support with said frame, balancing means fixed to said frame and connected with said rocking member adapted to 100 return said member to its normal vertical position when swung to either side of said vertical position when said balancing means becomes free from other forces to exercise its functions. 105

18. In a machine for operatively contacting a piece of work and a dressing wheel, a supporting structure, holding means for holding said piece of work, a driving shaft journaled in said structure, a crank-wheel, 110 a crank-pin radially and adjustably positioned on said wheel, a rack-bracket on said structure, a rack in sliding engagement with said rack-bracket, means operatively connecting said rack with said crank-pin, the 115 length of stroke of said rack being adjustably fixed by positioning said crank-pin with respect to the center of said crank wheel, a second rack-bracket on said structure, a second rack slidably engaging said 120 second rack-bracket, gearing operatively connecting said racks, means operatively connecting said holding means with said second rack, for giving a motion of reciprocation to said piece of work, and intervening 125 mechanism between said shaft and said crank-wheel for turning the same.

19. In a machine for applying a piece of work to a dressing wheel, a frame, a rocking member journaled to said frame, a driv- 130

ing shaft, a crank-wheel, a crank-pin radially and adjustably positioned on said wheel, a rack-bracket on said member, a rack in sliding engagement with said rack-bracket, means operatively connecting said rack with said crank-pin, the length of stroke of said rack being adjustably fixed by positioning said crank-pin with respect to the center of said crank wheel, a second 5 rack-bracket on said member, a second rack slidably engaging said second rack-bracket, means operatively connecting said racks, 10

other means operatively connecting said holding means with said second rack, whereby a motion of reciprocation is imparted to said piece of work, and intervening mechanism between said shaft and said crank-wheel for turning the same. 15

Buffalo, N. Y., Jan. 25, 1917.
